HOLE DIGGER

John W. Houston, Grinnell, Iowa

Application July 3, 1950, Serial No. 171,911

3 Claims. (Cl. 255—19)

1

My invention relates to the art of hole digging machines, and has as its principal object to provide a post hole digging machine employing an earth auger that is vertically slidably movable with respect to a driving head that is supported at a fixed elevation in a manner that permits uninterrupted rotation of the auger.

It is a further object of my device to provide a hole digger that is composed of two major sub-assemblies with a sliding power transmission linkage between them which permits the movement of one with respect to the other without interruption of the transmission of power from one to the other.

Still a further object of my invention is to provide a hole digger that has a single lever to control the elevation of the auger which is raised by winding a flexible member on a drum and lowered by the force of gravity.

In addition it is an object of my invention to provide a hole digger that has a removable auger bit with curved earth and root cutting peripheral blades.

Yet another object of my invention is to provide a hole digger that is durable in use and inexpensive to manufacture in terms of its operative life.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a view of my device as it appears when viewed from the rear of a prime mover on which it is mounted. Broken lines show the drawbar and one wheel of the supporting prime mover to show the relative position of the device to a prime mover on which it is mounted.

Fig. 2 is an enlarged top view of the main power transmission and control mechanism of my hole digger taken on the line 2—2 of Fig. 1.

Fig. 3 is a cross-sectional view of a portion of the mechanism shown in Fig. 2 and taken on the line 3—3 of Fig. 2.

Fig. 4 is a detail view of the beveled gear power separation point where power from the power transmission connecting linkage is directed to the two different powered portions of the digging and control elements taken on the line 4—4 of Fig. 3.

Fig. 5 is an enlarged view of the driving head of my device as it appears when viewed from one side of the prime mover on which the device is mounted and taken on the line 5—5 of Fig. 1.

2

Fig. 6 is a top view of the portion of my device shown in Fig. 5 and taken on line 6—6 of that figure.

Fig. 7 is an enlarged top view of the earth auger of my device taken on the line 7—7 of Fig. 1.

Fig. 8 is an enlarged side view of my removable auger bit taken on the line 8—8 of Fig. 1. Broken lines illustrate hidden portions of the bit and a fragment of the auger to show the relation between the bit and the auger.

Referring to the drawings I have used the numeral 10 to designate one leg of the L-shaped frame the longitudinal axis of which extends parallel to that of a prime mover on which the device is mounted when in use. A round drive shaft designated 11 is journaled in a bearing 12 mounted on one end of the frame leg 10. A second bearing designated 13 mounted on the cross member 14 of frame leg 10 serves as a support near the other end of shaft 11. The cross member 14 may be secured to the frame in any suitable manner preferably by welding. A clutch plate gear assembly designated 15 is mounted on the shaft 11 to be rotatable thereon except when it is in frictional contact with a second clutch plate designated 16 that is keyed to shaft 11 so as to rotate with but be slidably thereon. A spring 17 forces clutch plate 16 into contact with the clutch plate of assembly 15 by pushing on the end of the plate 16 and the washer 18 that is held in place by adjusting nut 19 and lock nut 20. This overload clutch is of standard form and is not claimed as invention. It is not deemed necessary, therefore, to explain the operation of the unit. The end of shaft 11 that extends beyond bearing 12 connects to a conventional power take-off from a prime mover such as a tractor or the like and representatively shown by the broken lines designated 21. A slot 22 in shaft 11 provides a key way for a sliding gear 23 both of which are for the purpose of making a power connection on some types of prime movers. As they comprise no part of the claimed invention, their operation is not described.

An idler shaft designated 24 is journaled at one end in a bearing designated 25 that is mounted on the cross member 14 of frame leg 10. Under shaft 24 a stub frame member 26 extends and supports a second bearing 27 for shaft 24. A gear 28 is rigidly secured to shaft 24 and is operatively associated with assembly 15 by means of a drive chain 29 so that shafts 11 and 24 rotate together as long as the overload clutch plates 15 and 16 do not slip over each other. A clutch guard rail designated 30 is rigidly secured to frame stub 26 and side of frame 10.

A first beveled gear designated 31 is mounted on the end of idler shaft 24 and is constantly in meshing relation with the beveled gear designated 32. A sliding shaft designated 33 that may have any cross-sectional configuration other than round is here shown in its preferable square shape, and is slidably mounted in a bearing designated 34 that rotatably supports the sliding shaft and also permits sliding movement of the shaft with respect to the bearing. The second beveled gear 32 is engaged and supported by the sliding shaft and the hole in the second gear should have substantially the same configuration as cross section of the sliding shaft. The purpose of this construction is to permit sliding movement of these two members with respect to each other without disturbing the chain of power transmission through them. All the bearings mentioned so far are secured on the frame leg 10, cross member 14, or frame stub 26 by means of like bearing caps all designated 35 secured to the frame in any suitable manner as by nut and bolt assemblies 36.

The sliding shaft 33 is the power connection between the source of power from the power take-off 21 to carriage generally designated 37. The sliding shaft is secured to the carriage as to be rotatable but otherwise fixed in relation to it. The carriage consists of two upstanding trapezoidal side pieces designated 38 and 39 respectively that are secured together by having suitable cross pieces rigidly secured to the side in any suitable manner as by welding or the like. These cross pieces have been designated 40 and 41 respectively. The carriage 37 rides on flanged wheels 42 above and retaining wheels 43 below track 44. The track is secured in any suitable manner as by slotted screws 45 or the like to the second leg 46 of the L-shaped frame. All the wheels are journaled on suitable axles secured to the carriage. A carriage movement control lever designated 47 is suitably hinged to the frame stub 26 and extends upwardly past sector 48 which is secured at its respective ends to frame stub 26 and a side member of frame leg 11 as shown in Fig. 2. A connecting rod designated 49 connects the lever to the lever 47 so that as the lever is moved past sector 48 the carriage 37 is rolled on track 44 which permits lateral adjustment of the carriage. The means for locking lever 47 in a given relation to sector 48 is a standard technique the description of which is deemed unnecessary. Figs. 1 and 2 taken together make the operation of this control quite clear.

The sliding shaft 33 transmits power to power a distribution point of three beveled gears. One designated 50 is secured to sliding shaft 33 and meshes with a winch beveled gear designated 51 that rotates about an axis at right angles to that of beveled gear 50. A winch power shaft designated 52 journaled in carriage 37 is secured to winch beveled gear 51 and rotates with it. A sprocket gear designated 53 is secured to the end of winch power shaft and transmits rotating movement to winch sprocket 54 through a drive chain 55. Winch sprocket 54 is secured to a winch idler shaft designated 56 that is appropriately journaled in carriage 37. Pinion gear 57 is secured to the end of shaft 56 which extends beyond side 39 of carriage 37. A winch drum 58 is appropriately journaled on its drum shaft 59 in the carriage 37. The winch axle has a female clutch plate brake drum 60 assembly secured to one end near pinion 57. A gear and

5 male clutch plate assembly 61 is mounted on the drum shaft 59 so that they are freely rotatable with respect to each other when the male and female clutch plates are not engaged. The gear of assembly 61 is in constant meshing relation with pinion 57 so that they always rotate together. A winch control lever designated 62 is hingedly secured to control lever support 63 that is in turn appropriately secured to the carriage 37 as by welding or the like. A clutch connecting bar designated 64 is secured to male plate gear assembly and the control lever 63 respectively so that movement of the lever 63 slides the assembly 61 on winch shaft 59. A brake band designated 65 loosely embraces the brake drum of assembly 60 by having the ends of the band yieldingly forced apart as shown in Fig. 3 by a spring designated 66. A bolt indicated by the numeral 67 extends through appropriate holes in the ends of the brake band, the spring, and extends upwardly through a pair of bored members the lower of which is designated 68 and the upper 69. An adjusting nut 70 and lock nut 71 hold the assembly together. Bored member 68 is rigidly secured to the brake band end adjacent it. Bore member 69 has a crank arm 72 rigidly secured to it so that any pull on the end of crank arm 72 tends to rotate bored member 69 with respect to its counter part unit 68. Since the ends of the bored members adjacent each other are machined to form complementary bias cut shoulders rotation of one with respect to the other tends to force the members apart so that the total space on the bolt occupied by the members 68 and 69 increases which reduces the space on the bolt for the spring and band ends thus tightening the brake band about the drum of assembly 60 to hold the winch drum in a given position. Appropriate connecting linkage designated 73 is hingedly secured at one end to the crank arm 72. The other end of linkage 73 extends through a hole in an ear 74 also secured on control lever 62. Lock nuts 75 and adjusting nuts 76 make it possible to adjust the relative point of actuation of the brake and clutch so that an extreme movement of the lever in either direction will cause one of these units to be engaged and the other to disengage. An intermediate position is also possible where the power will be disconnected from the winch and the brake disengaged simultaneously.

The carriage is the support for the auger boom 77 one end of which is secured in socket 78 on cross piece 41. Two like side braces 79 serve to support the weight of the boom by having their ends secured to collar 80 and the sides of the carriage respectively. The collar 80 is rigidly secured to boom 77 and has a bearing arm 81 extending downwardly from it to support one end of the primary auger drive shaft 82. The other end of shaft 82 is supported in a bearing 83 on cross piece 40 and the lower end of the shaft carries auger drive bevel gear 84. Gear 84 meshes with winch bevel gear 54. Thus all the gears of the power distribution point rotate simultaneously. Primary drive shaft 82 is connected by a universal joint 85 to one end of slip shaft 86 and the other end of slip shaft 86 connects to a second universal joint designated 87. The second universal joint connects slip shaft 86 to a short driving shaft designated 88 which short shaft is appropriately journaled in a shaft support arm 89 that is part of a bearing support generally designated 90. The bearing support 90 is hingedly mounted on the head frame designated 91 by means of stub shafts designated 92. The head

frame is hingedly secured to the end of auger boom 77 by means of a bearing member indicated by the numeral 93. This bearing member 93 is appropriately secured to the head frame as by nut and bolt assemblies 94 or the like. Because of the two hinged connections of the bearing support to the head frame and the head frame to the boom, it will be noted that the bearing support is universally jointed with respect to the boom. The bearing support has an upstanding fin designated 95 that is connected by rod 96 to the auger angle control lever 97. This control lever is hingedly secured to the boom 77 and moves in an arc adjacent sector 98. The lever may be disengaged and from the sector by retaining sector engaging rod 99 in a raised position. When the lever is so disengaged the bearing support is free to move with respect to the head frame. It is possible, however, to engage rod 99 in sector 98 and so hold the bearing support at an angle with respect to head frame 91.

The auger itself, generally designated 100 is secured to a shaft designated 101 which may be any shape other than round in cross section. It is here shown as preferably being square which is satisfactory and relatively inexpensive. This shaft 101 is vertically slidable through a beveled gear rotatable member designated 102. The opening in the rotatable member 102 is such a shape that the shaft 101 just fits it so that the shaft must rotate with member 102 which is appropriately journaled in the lower end of bearing support 90 as shown in Fig. 5. The shaft is stabilized with respect to bearing support 90 by a second bearing rotatable member designated 103 that is appropriately journaled in the top of the bearing support. The opening in the second rotatable bearing member 103 need not match the configuration of the cross section of shaft 101 but preferably does so to offer greater support for the shaft. The short shaft 88 has a beveled gear designated 104 that engages with the gear teeth of rotatable member 102 which completes the power transmission linkage to drive the auger 100. The elevation of the auger is regulated by the flexible members designated 105. These cables or like units are partially wound on winch drum 58 and are reeved over the pulleys 106 to provide a substantially straight upward pull to the auger. Flexible members 105 are secured to a collar member 107 that permits the auger and shaft 101 to rotate freely but will lift the auger and shaft 101 if raised by cable flexible members 105. When the winch control lever 62 is moved to engage the power of the prime mover by engaging the winch clutch as shown in Fig. 3, the winch drum 58 is rotated to reel in flexible members 105 to raise auger 100. When winch control lever 62 is moved to its other extreme position auger 100 is held at whatever elevation to which it has then been raised. When the lever 62 is placed in an intermediate position the winch drum is freely rotatable and gravity pulls the auger downwardly, the cables following. When the tension on the flexible cables 105 is thus released they might become disengaged from pulleys 106. To avoid this difficulty the curved cable guides 108 are secured to head frame 91 as by welding or the like.

The auger 100 is supplied with a removable cutting bit. The bit consists of a shaft terminating in a starting point designated as a unit by the numeral 109. A plate 110 is rigidly secured to the shaft and point assembly 109 as by welding or the like. Two like opposed cut-

ting blades 111 are detachably secured to plate 110 in any suitable manner as by the nut and bolt assemblies 112 or the like which permits the blades to be removed for sharpening or the like. In an emergency only one of these blades may be used in which case it must be set nearer to the center of shaft so that most extended portion of the cutting bit is within the area defined by a vertical projection of the periphery of the auger. Each cutting blade has a root cutting portion secured to it that curves in two directions. The blade unit curves to form a segment of a circle having substantially the same diameter as the auger and the cutting edge of the root cutting portion of the bit blades curves downwardly and rearwardly against the direction of rotation as seen in Fig. 8. This form of a blade gives a slicing action that gradually increases the pressure of the cutting edge on the root or like with no sudden jar to the auger and its driving mechanism.

The shaft portion of the shaft and starting point assembly slidably fits into an appropriate well in the auger 100 and is secured there by a pin designated 113.

In operation my post hole digger may be mounted on the draw bar 114 of a prime mover such as a tractor or the like. The auger boom 77 then arcs up past the rear wheel 115 as seen in Fig. 1. The prime mover is located near the place where the post hole is to be dug and the carriage positioned laterally by means of control lever 47 and the auger dropped. In most instances the bearing support control lever 97 has its sector engaging rod disengaged so that the auger is free to assume a vertical position with respect to the horizontal. The hole may be made at an angle, however, by the use of lever 97. The power may then be engaged to the auger, and it will bore into the earth. When the auger reaches its depth, the wing members 116 displace the earth that has been dug up by the auger so that dirt will not fall into the hole dug.

The control lever 97 is then moved to the position illustrated in Fig. 3 and the power from the prime mover rotates the winch drum to lift the auger from the completed hole.

Some changes may be made in the construction and arrangement of my hole digger without departing from the real spirit and purpose of my invention, and it is my intention to cover by my claims, any modified forms of structure or use of mechanical equivalents which may be reasonably included within their scope.

I claim:

1. An improvement in a hole digging apparatus designed to be mounted on a prime mover and having an upwardly and outwardly extending boom that supports an earth auger the improvement comprising; a head frame hingedly mounted on the outer end of said boom to swing in a vertical plane parallel to the longitudinal axis of said prime mover, a bearing support hingedly mounted in said frame to swing in a vertical plane at right angles to the plane in which said head frame swings, a shaft journaled in said bearing support on a substantially horizontal axis, a beveled gear secured to said shaft, a second beveled gear meshing with said beveled gear and journaled in said bearing support on a substantially vertical axis; said second beveled gear having a square bore in it, a bearing in said bearing support vertically spaced apart from said second beveled gear; said bearing hav-

ing a square bore through its center, a square shaft vertically slidably mounted in the bores of said second bevel gear and said bearing, a means for raising and lowering said square shaft; said earth auger being secured to and depending from the lower end of said square shaft, and a means for connecting said first mentioned shaft to a power source on said prime mover.

2. The post hole digging apparatus improvement of claim 1 further characterized by having a segment rigidly secured to said boom, a lever arm hingedly secured to said segment, means associated with said lever arm to secure said lever arm to said segment at various selectable points, and a rod hingedly secured to said lever arm by one end and to said bearing support at its other end.

3. The post hole digging apparatus improvement of claim 1 further characterized by hav-

ing means operatively associated with said boom, and said bearing support for selective manual tipping and securing of said bearing support relative to said frame.

JOHN W. HOUSTON.
